FOAM GENERATOR

Mace H. Bell, Rowayton, and Richard H. Yagami, Westport, Conn., assignors to General Foods Corporation, White Plains, N.Y.

Filed Nov. 3, 1971, Ser. No. 195,534

Term of patent 14 years

Int. Cl. D23—01

U.S. Cl. D23—17

FIG. 1

FIG. 2

FIG. 5

FIG. 5

FIG. 1 is a perspective view of a foam generator in accordance with our invention;

FIG. 2 is a right-hand side elevational view thereof;
FIG. 3 is a top plan view thereof;

FIG. 4 is a front elevational view thereof with a portion of the screen broken away;

FIG. 5 is a rear elevational view thereof;

FIG. 6 is a bottom plan view thereof; and

FIG. 7 is a sectional view thereof taken along the line 7—7 of FIG. 3.

The fragmentary broken line showing of a portion of the hose in FIG. 1 is for illustrative purposes only.

We claim:

The ornamental design for a foam generator, substantially as shown and described.
